NOVELTY BAROMETER

Raymond B. Kruskopf, St. Paul, Minn., assignor to Payne Enterprises, Incorporated, St. Paul, Minn., a corporation of Minnesota

Application July 14, 1958, Serial No. 51,768

Term of patent 14 years

(Cl. D52—7)

Fig. 1 is a front perspective view of a novelty barometer showing my new design; and

Fig. 2 is a right hand side elevation of the same.

A left hand elevation is similar to the elevation shown in Fig. 2 with the exception of the miniature figure.

I claim:

The ornamental design for a novelty barometer, as shown and described.
